(57) **CLAIM**

We claim the ornamental design for a medical instrument with waffle handle with bent shaft, as shown and described.

DESCRIPTION

FIGS. 1 and 2 are side elevations offset 180 degrees of a medical instrument with waffle handle and bent shaft showing our new design;

FIGS. 3 and 4 are top and bottom elevations offset 180 degrees of the medical instrument with waffle handle and bent shaft showing our new design;

FIG. 5 is a front view thereof; and,

FIG. 6 is a rear view.

The broken lines showing the remainder of the medical instrument are directed to environment and are for illustrative purposes only; the broken lines form no part of the claimed design.

1 Claim, 4 Drawing Sheets
